UNITED STATES PATENT OFFICE.

WILLIAM GLEDHILL, OF BARKISLAND, NEAR HALIFAX, ENGLAND.

WEIGHTING MOTION.

Application filed November 8, 1924. Serial No. 743,688.

To all whom it may concern:

Be it known that I, WILLIAM GLEDHILL, a subject of Great Britain, residing at Barkisland, near Halifax, England, have invented certain new and useful Improvements Relating to Weighting Motions, of which the following is a specification.

This invention relates to a loom weighting motion and has for its chief object to construct same in such manner that in addition to dispensing with heavy weights it will keep a uniform width of cloth from one end of a piece to the other by automatically decreasing the tension on the warp beam as the warp gets less in diameter.

According to this invention means are provided whereby variation in the diameter of the warp beam automatically varies the leverage which a weight exerts on a pivotally mounted bar or whip roller over which the warp threads from the beam pass.

In the accompanying drawings:—

Fig. 1 is a rear view, and

Fig. 2 an end view of part of a loom fitted with a weighting motion in accordance with this invention, and

Fig. 3 is a section of a portion of the mechanism looking in the direction of the arrows 3—3 in Fig. 2.

30 A indicates a whip roller that is rotatably mounted in two arms α which are rigidly fixed on a shaft α^1 which is carried by brackets α^2 detachably secured on the loom end frames B and formed with recesses α^3 to enable the shaft α^1 to occupy different positions. The arms α are connected to the upper ends of ropes or chains c which pass around the necks or ruffles c^1 of the warp beam C. The lower ends of the ropes or

40 chains are attached to a bar c^2 that is cranked at c^3 and mounted in levers c^4 . These levers are pivoted at c^5 and resistance is offered to their upward movement by strong springs c^6 . To enable the weight to be taken off the

45 ropes or chains c when it is required to turn the beam back, or remove it, the cranked rod c^2 is provided with a handle c^7 which can be turned to raise the rod and so take the tension off the ropes or chains. Pivottally mounted on the stud c^8 is an arm D carrying a weight d which may be fixed or detachable.

50 A portion of the arm D is curved at d^1 and operating in conjunction with this curved portion is a roller d^2 which is pivotally mounted on a stud d^3 which forms a spacing member for two plates d^4 which are pro-

vided at their upper ends with another spacing member d^5 . The latter is connected by a link d^6 and nut d^7 with an arm d^8 that is rigidly fixed on the shaft α^1 . The device for automatically regulating the leverage exerted by the weight lever D on the whip roller A as the warp beam C decreases in size comprises a plate or shoe E. This plate is pivotally mounted on the upper end of an arm e that is rigidly fixed on a shaft e^1 . This shaft is rotatably mounted in a bracket e^2 that is attached to a portion of the loom frame and a portion of such shaft projects beyond the loom end frame and has rigidly fixed on it an arm e^3 . Pivottally attached to this arm is a bar e^4 which passes between the plates d^4 and is secured thereto by a bolt or screw e^5 which also secures the plates together. The bar e^4 is formed with a number of perforations e^6 to enable the position of the roller d^2 to be varied in relation to the fulcrum c^5 . With this construction when the warp beam is full the parts occupy the position shown, the arm d^2 being in its nearest position in relation to the fulcrum c^5 and the weight d occupying the maximum amount of leverage upon the whip roller A. As the warp beam decreases in size the plate or shoe E moves with it towards the centre 80 of the warp beam and the roller d^2 travels along the curved portion of the lever D away from the fulcrum c^5 with the result that the weight d exerts a gradually decreasing leverage on the whip roller A and so maintains a constant tension on the warp threads C¹. When weaving heavy cloth the plates d^4 are moved nearer to the pivoted end of the perforated bar e^4 so as to bring the roller d^2 nearer to the fulcrum c^5 and increase the leverage exerted by the weight d on the whip roller A. The shaft α^1 would also be mounted in the recess α^3 as shown in Fig. 2 of the drawings. To weave light cloth the shaft α^1 would be placed in the recess at the right hand end of the bracket α^2 and the plates d^4 would be moved towards the left hand end of the bar e^4 and connected therewith. F indicates a stop for supporting the weighted arm D when the handle c^7 is turned in a direction to slacken the chains c for enabling the beam C to be taken out or turned back.

What I claim as my invention and desire to secure by Letters Patent in the United States, is:—

1. In a loom weighting motion, the combi-

nation with a warp beam, of flexible connections wound on the necks of the warp beam, pivoted arms connected to the upper ends of the flexible connections, a whip roller carried by pivoted arms, an arm arranged in rigid connection with such arms, a pivotally mounted weighted arm, a connection between the weighted arm and the arm last mentioned, and means for automatically moving said connection to decrease the leverage exerted by the weighted arm on the whip roller as the beam decreases in diameter.

2. In a loom weighting motion, the combination with a warp beam of flexible connections wound on the necks of the warp beam, pivoted upper and lower arms connected to the respective ends of the said flexible connections, springs for exerting pressure against said lower arms, a whip roller carried by the upper arms, an arm arranged in rigid connection with such arms, a curved weighted arm pivoted below such arm, a connection between said arm and the curved weighted arm, said connection being provided with a roller adapted to run along the curved surface of the weighted arm, a two armed lever provided at one end with a shoe adapted to rest against the warp on the warp beam and at the other end with a link adjustably attached to the aforesaid connection whereby the leverage which the weighted arm exerts on the pivotally mounted whip roller decreases as the beam decreases in diameter, means for releasing the tension on the flexible connections and means for supporting the weighted lever when said tension is released.

exerted by the weighted arm on the whip roller as the beam decreases in diameter.

3. In a loom weighting motion, the combination with a warp beam of flexible connections wound on the necks of the warp beam, pivoted upper and lower arms connected to the respective ends of the said flexible connections, springs for exerting pressure against said lower arms, a whip roller carried by the upper arms, an arm arranged in rigid connection with such arms, a curved weighted arm pivoted below such arm, a connection between said arm and the curved weighted arm, said connection being provided with a roller adapted to run along the curved surface of the weighted arm, a two armed lever provided at one end with a shoe adapted to rest against the warp on the warp beam and at the other end with a link adjustably attached to the aforesaid connection whereby the leverage which the weighted arm exerts on the pivotally mounted whip roller decreases as the beam decreases in diameter, means for releasing the tension on the flexible connections and means for supporting the weighted lever when said tension is released.

In testimony whereof I affix my signature.
WILLIAM GLEDHILL.
